ELECTRIC SWITCH

Eliot Noyes, New Canaan, Conn., assignor to General
Electric Company, a corporation of New York

Filed Dec. 8, 1959, Ser. No. 58,597

Term of patent 14 years

(Cl. D26—13)

Fig. 1

Fig. 2

Fig. 3

Fig. 4

FIGURE 1 is a perspective view of an electric switch embodying my new design;

FIGURE 2 is a reduced side elevational view;

FIGURE 3 is a reduced front elevational view;

FIGURE 4 is a reduced end elevational view thereof. The dominant features of my design reside in the portion shown in full lines.

The rear, not shown, is conventional.

I claim:

The ornamental design for an electric switch, as shown and described.
